RADIATOR

Fredrik W. Hvoslef, Kohler, Wis.

Application March 25, 1935, Serial No. 12,940

12 Claims. (Cl. 22—203)

My invention relates to improvements in radiator units of a type wherein a plurality of thin metal fins are integrally united to a central, hollow cast metal core portion during the casting thereof, and the objects of my invention are, first, to provide a method of manufacturing such a radiator whereby the fins are integrally united with the core portion during the casting thereof; second, to provide means for preventing the warping and deformation of the fins during the casting and subsequent cooling of the core portion; and third, to prevent cracking of the core by the aforesaid warping of the fins.

I attain these objects by the means illustrated in the accompanying drawing, in which Figure 1 is a top plan view of the radiator, Fig. 2 is a side elevation of an end portion of the radiator, partly in section; Fig. 3 is an end elevation of the radiator showing the construction of the fins, and Fig. 4 is a sectional view taken along the line 4—4 of Fig. 1.

Similar numerals refer to similar parts throughout the several views.

In the drawing the numeral 1 indicates the central portion or core, formed with the hollow portion or cavity 2 adapted to serve as a conduit for steam or other heating medium. The end portions of the core 1 are preferably enlarged as at 3 and provided with the bore 4 adapted to receive a connecting nipple whereby connection may be made to a supply pipe for the heating medium or to a header which in turn has a supply connection to the heating medium. It is desirable, particularly where hot water is to be the heating medium, to provide the core with a second bore 5 likewise adapted to receive a connecting nipple whereby a circulating connection may be established through the cavity 2. It will be understood that the bores 4 and 5 are provided at each end of the unit and that, if desired, any number of units may be connected end to end by means of nipples.

A plurality of fins 6, preferably stamped from sheet metal, and having a flat body portion, are integrally attached to the core 1 during the casting thereof in the following manner. The fins are formed with a central upwardly extending slot 7 whereby the fin is bifurcated for a portion nearly equivalent to the height of the core 1. The slot 7 is somewhat narrower than the width of the core 1, so that when placed in the mold for the core 1 the fins protrude into the mold cavity and upon casting are firmly welded into the molten metal which extends to cover the portion adjacent the slot 7 as shown by the dotted

line of Figure 4. As shown in Fig. 2, a number of the fins are relatively short to accommodate the enlarged portions 3 of the cores.

However, the expansion and contraction of the casting during the pouring and subsequent cooling of the casting places severe stresses upon the fins and tends to buckle or deform them, a difficulty which has heretofore rendered this method of forming a radiator impracticable. An important feature of my invention is the provision of means for preventing the deformation of the fins during casting and cooling.

To this end I provide a novel configuration of the fins 6 as follows. The fins 6 are provided with a second slot 8 which joins the slot 7 at one end and extends upwardly to a point near the top of the fin. The fin 6 is also notched or indented as at 9 at points equidistant the slot 8, the indentations 9 extending into the fin 6 to a point approximately even with the slot 8 but leaving a pair of narrow spans 10 between the slot 8 and the indentations 9. There is thus formed the tongue 11 between the indentations 9 and joined to the body of the fin only by narrow spans 10.

With this construction it will be found that any stress upon the fin will be transmitted to the tongue 11 and will cause bending thereof, and that the yielding of this tongue relieves the strain sufficiently to prevent bending or deformation of the fin proper, and also to prevent cracking of the core casting due to the strain placed thereon by the deformation of the fins. To facilitate this action the tongues 9 are preferably bent slightly from the vertical before being placed in the mold as shown in Figures 1 and 2. Upon casting, the bending or deforming of the tongues will continue in the direction in which they are originally bent, thus by placing the fins in the mold so that the tongues are all bent in one direction or all bent inwardly toward the center the further bending of the tongues does not detract from the appearance of the unit.

The fins 6 are preferably provided with flanges 12 bent at approximately right angles thereto and extending practically to the next fin, thus the unit forms in effect a closed conduit for the passage of air therethrough past the core 1 and the fins 6.

The end portions 3 of the core 1 may be provided with a downwardly extending flange 13 drilled at 14 to receive a bolt for attaching the unit to a header or to another unit. The slot 8 is preferably elliptical in form to allow the

passage therethrough of a draw rod for the same purpose.

I prefer to form the core 1 of cast iron and the fins 6 of sheet iron or steel, but any suitable material may be used.

5 The radiator unit as thus constructed is cheap, durable, of high thermal efficiency and much lighter in weight than an equivalent amount of the ordinary tube style radiation. On account 10 of its high efficiency and the relatively small space required for its installation it is particularly adapted to installation in recesses in the walls, concealed radiation and forced ventilation heating systems.

15 It will be obvious that units of this type may be used for cooling as well as heating purposes by circulating a cooling instead of a heating medium therethrough.

I claim:

20 1. In a radiator, the combination of a cast metal core having a conduit forming hollow therein and a plurality of fin members integrally united therewith during the casting thereof, said fin members comprising a substantially flat body portion, a pair of indentations therein, a deformable tongue between said indentations, and a slot positioned at the base of said tongue and adjacent an extremity of said core.

25 2. In a radiator, the combination of a cast metal core having a conduit forming hollow therein and a plurality of fin members integrally united therewith during the casting thereof, said fin members comprising a substantially flat body portion, a pair of indentations therein, a tongue deformable upon strain on said body portion and positioned between said indentations, said tongue being bent slightly from the plane of said body portion whereby to influence the direction of the aforesaid deformation of the tongue, and a slot 30 positioned at the base of said tongue and adjacent an extremity of said core.

35 3. A fin adapted to be integrally united with a cast metal core during the casting thereof to form a radiator, said fin comprising a body portion and a deformable tongue attached to said body portion by a plurality of relatively narrow spans.

40 4. A fin adapted to be integrally united with a cast metal core during the casting thereof to form 45 a radiator, said fin comprising a body portion and a tongue deformable upon strain on said portion and attached to said body portion by a plurality of relatively narrow spans and bent slightly from the plane of said body portion whereby to aid the aforesaid deformation and influence the direction thereof.

45 5. In a radiator, the combination of a cast metal core, a conduit therein and a plurality of fin members, said fin members comprising a body portion integrally united with said core and a portion attached to said body by relatively narrow spans and deformable upon thermal expansion or contraction of said core prior to the occurrence of any deformation of said body portion.

60 6. A fin for a heat exchange device comprising a substantially flat body portion and a tongue attached thereto and deformable upon strain on

said body portion, said tongue being bent from the plane of said body portion at an angle acute thereto.

7. A fin for a heat exchange device comprising 5 a body portion, a slot therein adapted to receive the core of a heat exchange device, a pair of indentations in one edge of said body portion, a tongue formed therebetween, and a second slot in said body portion between said first mentioned slot and the base of said tongue.

10 8. A fin for a heat exchange device comprising a body portion, a slot therein adapted to receive the core of a heat exchange device, a pair of indentations in one edge of said body portion, a tongue formed therebetween and bent slightly 15 from the plane of said body portion to aid deformation of said tongue upon strain on said body portion, and a second slot in said body portion between said first mentioned slot and the base of said tongue.

15 9. A radiator fin comprising a substantially flat body portion provided with a radiator core receiving slot, a tongue attached to said body portion by relatively narrow spans, and a second slot in said body member between said first mentioned 20 slot and the base of said tongue.

25 10. A radiator fin comprising a substantially flat body portion provided with a radiator core receiving slot, a tongue attached to said body portion and deformable upon strain on said body 30 portion, and a second slot in said body member, said second slot extending between said first mentioned slot and the base of said tongue.

35 11. The method of forming a sheet and cast metal structure which comprises placing a plurality of sheet metal members in a mold, casting a core portion of cast metal thereon whereby to weld said sheet metal members to said core portion during the casting thereof, said sheet metal members protruding beyond said core portion, 40 and preventing the deformation of the main or body portion of said sheet metal members by the stresses set up by expansion and contraction during casting by providing the protruding portion of each of said sheet metal members with 45 a portion more easily deformable upon strain on said sheet metal member than the rest of said sheet metal member said deformable portion being positioned adjacent the outer edge of said sheet metal member.

50 12. The method of forming a sheet and cast metal structure which comprises placing a plurality of sheet metal members in a mold, casting a core portion of cast metal thereupon and relieving the strain on said sheet metal members 55 and preventing deformation thereof by the stresses occasioned during casting by providing the protruding portion of said sheet metal members with a portion deformable upon stress on said sheet metal member prior to the deformation 60 of the body portion of said member and partially deforming said deformable portion from the plane of said sheet metal member prior to said casting operation said deformable portion being positioned adjacent the outer edge of said sheet metal 65 member.
